UNITED STATES PATENT OFFICE

2,622,333

MUSIC DRAFTING APPARATUS

Ephraim E. Magnuson, Arlington, Mass.

Application July 2, 1949, Serial No. 102,839

2 Claims. (Cl. 33—174)

1

This invention relates to music drafting machines, and pertains more particularly to improvements in apparatus for manually inscribing in proper spaced relation on a blank musical staff, printed or otherwise reproduced on a paper sheet, the various notes and other musical symbols of a manuscript score, so that the inscribed sheet may be photographed and reproduced in multiple copies by printing.

The principal purpose of the invention is to provide a musical drafting machine having a template movable over the staff sheet in two directions and manually adjustable in each direction, with respect to the staff, the template having openings of various shapes through which the musical notes and symbols may be manually inscribed on the staff in proper relation to the staff lines and to each other, according to the musical value of the notes or symbols the note spacing designated on a manuscript score.

Additional objects of the invention and novel features of the musical drafting machine will become apparent from the following description of the recommended embodiment of the invention shown on the accompanying drawings, and will be pointed out in the appended claims. It will be understood, however, that the structural details of the apparatus herein illustrated and described may be varied to suit particular purposes or conditions without departing from the essence of this invention as set forth in said claims.

In the drawings,

Fig. 1 is a plan view of a music drafting machine constructed in accordance with this invention;

Fig. 2 is a side elevation looking to the right of Fig. 1;

Fig. 3 is a front elevation looking to the left of Fig. 2;

Fig. 4 is an enlarged plan view of the adjustable template and its movable carriage, forming part of the machine;

Fig. 5 is a detail elevation taken on line 5—5 of Fig. 4;

Fig. 6 is a bottom view of the template carriage shown in Fig. 4;

Fig. 7 is a transverse section on line 7—7 of Fig. 4;

Fig. 8 is an enlarged fragmentary plan view 50 of the table and the machine on which the staff sheet is placed, showing locating plugs for properly aligning the staff sheet on the table; and

Fig. 9 is a section on line 9—9 of Fig. 8.

In the particular embodiment chosen for the 55

2

purpose of illustration, the music drafting machine comprises a table 11 suitably mounted in horizontal position adjacent an inclined back panel 12 which may be made of aluminum or other suitable material and constitutes the front of a cabinet 13 containing drawers 14 for drafting instruments and equipment, the cabinet, panel and table being supported in elevated position upon a frame 15. A closed compartment 16 is preferably located beneath the table 11 and contains a light bulb 17 which may be mounted on a hinged door 18 affording access to the compartment. The table 11 and compartment 16 are so arranged with respect to the inclined panel 12 as to provide a space between the back of the table and the panel, so that a spacing guide chart 19, pivoted at 20 to the panel, may be swung downwardly between the board and the table (as indicated by the broken line position of Fig. 3) for a purpose to be hereinafter described.

A carriage 21, extending transversely of the table 11 is mounted for movement longitudinally of the table, on suitable rails or guides extending 25 along the front and back of the table 11. As here shown, the front rail 22 consists of a metal strip suitably fastened in spaced parallel relation to the front edge of the table, and the back guide rail 23 has an upper portion of angular cross section providing a pointed ridge which is received in complementary slots 24 in the bottoms of the back wings 25 of the carriage 20 (Figs. 2 and 6). The front end of the carriage has a bottom shoe 26 which rides on the rail 22.

The carriage or platform 21 preferably consists of a metal plate provided on its underside (Figs. 6 and 7) with a shaft 27 which carries the bearings 28 of a plate 29, one edge of which is provided with a rack 30. A template holder 31 mounting a template 32 is connected by suitable struts 33 to the plate 29, so that the template is supported at one side of the carriage below the plane of the plate 29 which is slideable beneath the top of the carriage 21 on the shaft 27.

A pinion 34 is pivotally mounted under the carriage platform, in operative engagement with the rack 30 of the plate 29, by a shaft 35 carrying a knob 36 disposed above the carriage and equipped with a pointer 37 movable over a circular scale 38. Thus by rotating the knob 36, the template 32 may be moved along the carriage, transversely of the table 11, and the position of the template relative to the carriage may be adjusted by regulation of the pointer 37 which preferably has a downwardly projecting

tip 38 engageable in notches 39 of the dial scale 38 (Fig. 5). The notches are so spaced that movement of the pointer top from one notch to the next adjacent notch moves the template a distance equivalent to half the space between the lines of a musical staff placed beneath the template. The carriage is manually movable longitudinally of the table on the guide rails 22 and 23, as aforesaid, so that the position of the template may thus be adjusted in two directions, both longitudinally and transversely of the table 11.

The template is preferably disposed a short distance above the surface of the table 11 which may be provided with a linoleum cover 40, on which the sheet of staff paper 41 is placed, so that the template may be freely moved without disturbing the sheet 41. The staff sheet is located in proper position on the table top by aligning the staff with scribed lines 42 on the surface of transparent plugs 43 fitted in openings in the table (Figs. 8 and 9), the lines of said plugs being illuminated by the light bulb 17 in the underlying compartment 16. The sheet may be fixed in position by thumb tacks, or otherwise. The staff sheet 41 has conventional staff lines 44, printed or otherwise reproduced thereon, and the clef signs may also be printed on the staves. Otherwise, the staves are blank, and the mechanical notes and other symbols are manually inscribed on the staves by inserting a pen or other scribing instrument through one or more of a series of openings 45 cut through the template 32. The sheet 41 is so located by the plug lines 42 that the left-hand ends of the staves thereon are in a line intersecting the pivot 20, when the staff lines are parallel to guide rail 23.

The longitudinal position of the carriage 21 with respect to the table 11 is regulated by registering the scribed lines 46 on an index tab 47 fastened to the back of the carriage (Figs. 1 and 4) with graph lines inscribed on the pivoted, sector-shaped chart 19. The respective index lines 48 preferably relate to the position of an eighth note, a quarter note, and a half note. The registration of one of said lines with a selected guide line of the sector chart regulates the longitudinal spacing on the staff 44 of notes or symbols of differing value, inscribed through the openings 45 of template 32. The desired spacing of the notes is usually marked on the manuscript score which is to be reproduced by the drafting machine. Usually an eighth note requires six spaces from the preceding note, a quarter note takes eight spaces, and a half note takes ten spaces; but this relationship is more or less arbitrary and obviously subject to variation. In any event, the total note space of the staff and the relative spacing of the notes, is indicated on the draft or manuscript score which is reproduced by the user of my music drafting machine.

In order properly to space the notes longitudinally of the staff, in accordance with such designations, the sector chart is preferably inscribed with lines 47 radiating from the pivot 20 and with parallel lines 48 which are disposed in spaced parallel relationship to the margin 49 of the sector disc 19. The spacing of the parallel lines 48 is a measure of the spacing distance of the notes or symbols to be inscribed on the staff 44 of the sheet 41. As shown in Figs. 1 and 3, the distance between the lines 48 is equivalent to ten musical spaces on the staff, but it will be evident that the chart 19 may have parallel guide lines spaced at a distance equivalent to one musical space (or

any other multiple), if desired. The spacing values of the guide lines 48 may be marked on the chart, as shown in Fig. 3, for the convenience of the user, it being understood that the numerical indications progress from the line of origin 49 (which passes through the pivot 20) to the opposite side of the sector chart 19. The radial lines 43 are for the convenience of the user in setting the position of the chart with respect to the index tab 47, and may be omitted if not required for that purpose.

As is apparent, the chart 19 provides a proportioning rule by which any selected total staff space is divided, along the radial lines 47, into unit spaces of uniform value corresponding to the spacing of the notes or symbols to be inscribed on the staff sheet 41. The pivoted guide chart 19 may be held in adjusted position by any suitable fastening or clamping means such, for example, as the clamp 50 and nut 51 of Fig. 3.

In setting the operative position of the guide chart 19, it is swung on the pivot 20 until the particular guide line 48 having a value equal to the total spacing of the staff to be reproduced, intersects the edge of the index tab 47 at a point in line with the right hand ends of the blank staves 44 on the sheet 41. The index lines on tab 47 may then be registered with appropriate guide lines 48 on the chart, to locate the desired aperture of the template 32 longitudinally of the staff sheet for the correct spacing of a particular musical note or symbol from the left hand end of the staff 44.

The transverse position of the template is then adjusted by turning the knob 36 until the opening for the note to be inscribed is properly located above the appropriate space of the staff, as shown on the manuscript score. The notches 39 of the index dial 38 may be so arranged that by moving the pointer 37 from one notch to the next notch, the position of the inscribed note would be moved from a line to a space, or vice versa. The template 32 is preferably of transparent material and may have scored lines, as indicated at 52 (Fig. 4) as a further register check with the lines of the staff on the sheet 11. The shape of the openings 45 in the template may take various forms, as desired by the draftsman, it being understood that two or more of the openings may be used in inscribing a single note such, for example, as the base, the stem and the flag of an eighth note; the template being moved by the knob to the appropriate transverse position for inscribing the individual elements of the note.

After the musical score of the manuscript has been thus reproduced on the staff sheet 41, the sheet may be photographed and the negative or positive prints used in making printing plates for reproducing the printed score in multiple copies. The use of the music drafting machine herein disclosed ensures correct formation and accurate spacing of the musical notes and symbols on the staff sheet 41, and offset or other printing plates photographically produced from such sheets, provide cleaner and clearer prints than the prints made by conventional methods.

I claim:

1. A music drafting machine for manually inscribing notes and symbols on a paper sheet displaying a musical staff, comprising a table for supporting the staff sheet, a carriage movable longitudinally of the table, means for guiding longitudinal movement of the carriage, an apertured template, means slidably connecting the template to the carriage for movement of the

template transversely of the table, manually operated means on the carriage for regulating said sliding movement, and visual indicating means associated with the carriage and table respectively for indicating longitudinally adjustable positions of the movable carriage, whereby successive positions of the template with respect to the table may be accurately regulated by inspection of said visual indicating means, according to the desired spacing of the notes or symbols inscribed on the staff sheet through the apertures of the template, said visual indicating means comprising a ruled chart pivotally mounted for angular movement with respect to said table, said chart having axis lines projected radially from its pivot and uniformly spaced, parallel guide lines traversing said radial lines, and an index on one end of said carriage, adapted to be moved into registration with the guide lines on the chart after the chart is swung on its pivot to bring a selected axis thereof into position for registration with said index.

2. A music drafting machine for manually inscribing notes and symbols on a paper sheet displaying a musical staff, comprising a table for supporting the staff sheet, a carriage movable longitudinally of the table, means for guiding longitudinal movement of the carriage, an apertured template, means slidably connecting the template to the carriage for movement of the template transversely of the table, manually operated means on the carriage for regulating said sliding movement, and visual indicating means associated with the carriage and table respectively for indicating longitudinally adjustable positions of the movable carriage, whereby successive positions of the template with respect to the table may be accurately regulated by inspec-
